UNITED STATES PATENT OFFICE.

WILLIAM SMITH HARRY, OF NEW YORK, N. Y., ASSIGNOR TO THE UNION CARBIDE COMPANY, OF CHICAGO, ILLINOIS.

ELECTRIC FURNACE.

SPECIFICATION forming part of Letters Patent No. 655,780, dated August 14, 1900.

Application filed August 15, 1899. Serial No. 727,279. (No model.)

To all whom it may concern:

Be it known that I, WILLIAM SMITH HARRY, a subject of Her Majesty the Queen of England, and a resident of the city of New York, 5 in the State of New York, have invented certain new and useful Improvements in Electric Furnaces, of which the following is a specification.

The present invention constitutes an improvement upon the invention described and claimed in my pending application, Serial No. 706,352, filed February 21, 1899; and its principal object is to provide for the automatic regulation of many furnaces by means 15 of a single motor apparatus and without the expense and complication which arise when a separate motor is employed for each furnace. The apparatus described in said application comprises an electric furnace, the 20 movable member or element of which is operatively connected with the motor, which is started, stopped, or reversed in such manner and at such times as to keep the amperes constant in the furnace and which 25 is controlled by electromechanical devices worked by the furnace-current itself. In that application there is contemplated the use of a motor for each furnace, so that there will be as many motors as furnaces, and 30 consequently there will be required many small motors and much undesirable complication. All motors when started continue to run on by reason of the inertia of their parts, even after their driving power has been 35 interrupted, and this defect is disadvantageous, because the motors tend to run on and in that way lower or raise the furnace-amperes after the current to the motors has been interrupted. Moreover, a slow and even 40 movement of the regulating element of the furnace is undesirable, because it causes the mixture in the furnace to form an arch which delays the response of the furnace regulation. It is one object of the present invention to 45 obviate these defects and disadvantages and to provide for shifting the regulating element of the furnace with a quick jerky motion, which causes the mixture to fall at once into the zone or region of reduction.

50 In the present invention use is made of motor apparatus which may be of any pre-

fferred character and which may be run continuously in one direction or may be reciprocating, power-transmission mechanism for independently connecting the regulating element of each furnace with the motor apparatus to shift it in either direction and for disconnecting the same, electromechanical controlling devices in operative position to the furnace-circuit and adapted to automatically actuate the power-transmission mechanism only when the variations of the furnace-circuit amperage exceeds certain predetermined limits, and thereby keep the amperes approximately constant in the furnace, and 60 a switch constructed and arranged to control the power-transmission mechanism by hand, to shift the regulating element in either direction, and to permit and prevent control by the electromechanical devices.

The nature, characteristic features, and scope of my invention will be more fully understood from the following description, taken in connection with the accompanying drawings, forming part hereof, and in which—

Figure 1 is a view illustrating a plant equipped with apparatus embodying features of my invention and showing at the left hand a motor apparatus which operates to shift the regulating elements of the furnaces shown 80 in the center of the figure and at the right-hand side, upon an enlarged scale, portions of the regulating elements. Fig. 2 is a diagrammatic view showing features of the invention, and Fig. 3 is a detail view illustrating power-transmission mechanism adapted for use in connection with my invention.

Referring to the drawings, a motor 1, which may be of any desired type, imparts reciprocating motion to a long bar 2, which is pivotally connected with the lower ends of rocker-arms 3, journaled in suitable supports, as 4. The bar 2 may extend the whole length of a building containing many electric furnaces 5, and it may be arranged back of and 95 beneath the furnaces, so as to be out of the way. Between the furnaces there may be provided platforms 6 for the accommodation of the attendants in charge, and at each furnace there is a shaft 7, arranged transversely 100 of the bar 2 and provided with ratchet-wheels 8 and 9, of which the teeth are arranged in

opposite directions, so that one ratchet-wheel is adapted to turn the shaft in one direction and the other is adapted to turn it in the other direction. The shafts 7 are operatively connected with the regulating element of the furnace. As shown, they are operatively connected with the rotatable furnace-bodies 10 by means of worm-gearing. Clearly the shafts 7 can be employed, if desired, to shift the electrodes, and in such case the electrodes would become the regulating element of the furnace. In use the rocker-arms 3 oscillate continually about their points of pivotal support, which, as shown, are in line with the shafts 7. At the upper ends of these arms are pawls 11 and 12. When the pawl 11 is in engagement with the ratchet-wheel 8, it serves to turn the shaft 7 in one direction, and when the pawl 12 is in engagement with the ratchet-wheel 9 it operates to shift the shafts 7 in the other direction, and when both are out of engagement the shafts 7 are not turned at all. The described movements of the shafts 7 can be availed of to shift the regulating element of the furnace, and thus keep the amperes in the furnace-circuit constant, as will be hereinafter described. Moreover, the motions imparted by the pawls to the shafts 7 are somewhat jerky, and thus prevent the formation of arches in the mixture of the furnace. There is, moreover, no deleterious result, such as would be brought about by the inertia of moving parts. The means whereby the power-transmission mechanism is controlled are hereinafter more particularly described; but I may now call attention to the fact that when the pawls 11 and 12 are both clear of their corresponding ratchet-wheels, which is their position when unrestrained, the movable member of the furnace may be shifted, for example, by means of a hand-bar. For this purpose the shaft 7 is shown as provided with appropriate openings 13 for the insertion of such a bar. The attendant in charge from the platform 6 may readily manipulate the bar when necessary for this purpose. A description will now be given of the circuits by means of which the movements of the power-transmission devices are controlled.

14 and 15 are the conductors which supply current to the electrodes.

16 is a small transformer, of which the primary is the furnace-circuit itself, (amperes,) and the secondary (amperes) in the wire that surrounds it will be, as is well known, a small portion—say one one-hundredth part—of the furnace-amperes. The current in the secondary circuit, through suitable instrumentalities to be presently described, magnetizes and demagnetizes one or the other of the pawls 11 and 12, and thus serves to control the movement of the regulating member. In this connection it may be stated that the pawls 11 and 12 are each provided with diamagnetic counterweights, as shown. The current from the transformer 16 operates a

solenoid 17, so that when the amperage in the furnace-circuit is high the solenoid lifts its iron core 18, which likewise falls when the furnace-amperage is low. Attached to the iron core 18 is an insulated centrally-pivoted beam 19, carrying on its arms contact-bridges, substantially as illustrated. When the iron core 18 is drawn into the solenoid, it will cause one of these bridges to enter mercury-cups 20 and 21, by which a circuit is closed that causes one of the pawls of the power-transmission mechanism to engage its corresponding ratchet-wheel, and thus rotate the furnace so as to cause the amperes in it to be reduced. Should the current in the furnace be too low, the core 18 will fall, as shown in the drawings, closing a circuit by way of the cups 22 and 23, which causes the other pawl to come into action, and thus to turn the furnace in the opposite direction, which causes the current in the furnace to increase. In close proximity to the various furnaces are placed manual switches 24, which are accessible to the attendant in charge from the platform 6. Each switch gives control of the power-transmission mechanism from a point near the furnace to which it appertains. The solenoids and mercury-cups, of which there is a set for each furnace, may be located at a distance from the furnaces and in a position free from dust and dirt. To illustrate this, they are shown in a separate room or building on Fig. 1. The type of switch illustrated more particularly in Fig. 2 is known in the art as a "three-pole double-throw" switch. In the position shown the automatic mechanism will operate the power-transmission mechanism; but if it is desired to stop the furnace the switch is thrown in the opposite position. This causes the power-transmission mechanism to turn the furnace the other way, and it also short-circuits the solenoid 17, so that it has no power to lift the beam 19 out of the mercury-cups 22 and 23. In order to effect this, the poles on the three-pole switch are reversed, as shown and as hereinafter described. The motor apparatus will continue to turn the furnace until the attendant pulls the three-pole switch out of its contacts—that is to say, into a plane at right angles with the plane of the paper of the drawings. To start the furnace again, the attendant has only to insert the switch into its poles in the position shown in the drawings. For the sake of a further description circuits will now be traced, and in this connection it may be stated that the circuit 14 15 of the electrodes is assumed to be derived from some appropriate source and that 25 represents means by which current may be supplied for the purpose of magnetizing and demagnetizing the pawls 11 and 12 in order to change the direction of motion of the regulating member of the furnace. When the furnace is operating under automatic control, the switch 24 occupies the position shown. Under these circumstances there is a circuit from the

transformer 16 by conductors 26 and 27 to the solenoid 17, by conductor 28 to common return-conductor 29, and by conductor 30 back to the transformer 16. From the source 5 of current 25 there is a circuit which magnetizes, and consequently puts into action, one or the other of the pawls 11 and 12 to shift the regulating member of the furnace in one direction or the other, according to the position 10 of the beam 19. When the latter is in the position shown in Fig. 2, this circuit is by way of the conductor 32 to cup 22, by bridge-piece to cup 23, by conductor 33 to the central arm of the switch 24, through the same by conductor 34, through the coil 35 to the conductor 36, and thence to the common return. The passage of the current through the coil 35 magnetizes the pawl 11, thereby causing 15 it to engage its ratchet-wheel 8 and to thus shift the regulating element of the furnace in the appropriate direction for effecting the requisite change in the amperage of the furnace-circuit. When the beam 19 has been shifted into its other position, there is a circuit from 20 the source of current 25 by way of the conductor 37 to the cup 20, by way of the bridge-piece to the cup 21, by conductor 38 to the left-hand arm of the switch 24, by way of the conductor 39 to the coil 40, through the same, 25 and thence by the conductor 36 to the common return. Current traversing the coil 40 magnetizes the pawl 12, whereby it is attracted into engagement with its ratchet-wheel 9, and thus serves to rotate the furnace in the 30 opposite direction. When the hand-switch 35 24 is turned down through one hundred and eighty degrees, the first step toward stopping the furnace has been taken, and the circuits under these circumstances will be traced. 40 The circuit of the transformer 16 is short-circuited through the conductor 26, the right-hand arm of the switch, the conductor 41, and the upper portion of the conductor 30. The result of this is that the weight of the core 17 45 shifts the lever 19 into the position shown in the drawings. At the same time the conductor 33 is connected by way of the center pole of the switch, so as to energize the coil 40, with the result that the pawl 12 turns the 50 receptacle 5 in a counter-clockwise direction, thus uncovering the electrodes by drawing the product away from them. As soon as this has been accomplished the switch may be thrown into its third position, which is at 55 substantially ninety degrees to the plane of the paper. The result of this is the reestablishment of the circuit 26 27 28 29, so that the core 18 is drawn into the solenoid, thus depressing the right-hand portion of the lever 60 19. In this position of the switch 24 the circuits that control the pawls 11 and 12 are broken at the switch, and they therefore, under the influence of their counterweights, are held clear of the ratchet-wheels, and the furnace 65 remains at rest. Since the right-hand arm of the switch is depressed, it follows that as soon as the circuit is completed at the

switch 24 by turning it into the position shown in the drawings the circuit will be completed from the source 25 by 37, by cup 20, 70 by bridge-piece to cup 21, by 38 to left-hand arm of switch, by conductor 39, coil 40, conductor 36, and conductors 29 and 31 back to the source 35. Thus the pawl 12 is brought into action, and the furnace will commence 75 to run in a counter-clockwise direction, which is desirable in starting, and will continue to run in that direction until the core 18 is shifted in the manner described and by reason of changes in the furnace-circuit. To start the 80 furnace again, the switch 24 is again thrown into the position shown in the drawings, and the circuits above described are again completed, so as to reestablish the automatic control of the furnace. 85

The core 18 of the solenoid 17 and also the pivotal lever 19 respond to every change in the amperage of the furnace-circuit, even to changes which are permissible and incident to the process, whereas the local circuit, controlled by the contact-bridges and mercury-cups, is only made and broken when the variations in the furnace-circuit exceed predetermined limits depending upon the relation of the mercury-cups to the contact-bridges. 90 The result of this is that the movable element is shifted only in response to and so as to correct material variations in the furnace-circuit. The use of this apparatus also permits of the location of the solenoid and mercury-cups remote from the dust of the furnace, and it also insures positive engagement of the pawls 11 and 12. 95

It will be obvious to those skilled in the art to which my invention appertains that modifications may be made in details without departing from the spirit thereof. Hence I do not limit myself to the precise construction and arrangement of parts herein set forth, and shown in the drawings; but, 105

Having thus described the nature and objects of my invention, what I claim as new, and desire to secure by Letters Patent, is— 110

1. Means for regulating an electric furnace having a movable element and a motor for working it which means comprise regulating relay apparatus responding to the furnace-circuit, and devices worked by the relay for imparting motion from the motor to the movable element, said devices arranged to respond only to predetermined variations in the furnace-circuit thereby keeping the furnace-current approximately constant. 115

2. Means for regulating one or more electric furnaces which comprise motor apparatus, furnaces and their movable elements, power-transmission mechanism for independently connecting the movable element of each furnace with the motor apparatus to shift it in either direction and for disconnecting the same, electromechanical controlling devices in operative position to the furnace-circuits and adapted to automatically actuate the power-transmission mechanism to keep the 120

125

130

amperes constant in the furnaces, and switches constructed and arranged to control the power transmission by hand, to shift the regulating elements in either direction, and 5 to permit and prevent control by the electromechanical devices, substantially as described.

3. In combination an electric furnace and its movable element, a positively-driven reciprocating rocker-arm provided with two pawls, ratchet-wheels connected with the movable element of the furnace and whereof one is driven in one direction by one pawl and the other is driven in the opposite direction by the other pawl, two coils respectively adapted to magnetize one of the pawls, and electromechanical devices responding to the furnace-circuit and adapted to pass current through one or the other of said coils, substantially as described.

4. In combination a furnace and its movable member, ratchet-wheels for shifting the movable member in one direction or the other, pawls normally out of range of said ratchet-wheels, means controlled by the current through the furnace for shifting said pawls

into operative position, and a shaft interposed between the ratchet-wheels and the movable member of the furnace and provided with radial openings for the reception of a hand-bar, substantially as described.

5. In combination a series of furnaces having each a movable member, a reciprocating bar and means for reciprocating it, rocker-arms actuated by said bar, pawl-and-ratchet connections interposed between each rocker-arm and each furnace of a series and operatively connected with the movable member of each furnace, an electromagnet in operative position to each furnace-circuit, a switch controlled by each electromagnet, and a local circuit controlled by each switch and containing electromagnetic devices for throwing the pawls into and out of action, substantially as described. 45

In testimony whereof I have hereunto signed my name.

WILLIAM SMITH HORRY.

In presence of—

DORA STERNBERGER,
W. J. JACKSON.
